UNITED STATES PATENT OFFICE.

JOHN E. WIGGIN, OF STONEHAM, MASSACHUSETTS.

IMPROVEMENT IN EYELETING-MACHINES.

Specification forming part of Letters Patent No. 158,343, dated December 29, 1874; application filed July 24, 1874.

To all whom it may concern:

Be it known that I, JOHN E. WIGGIN, of Stoneham, in the county of Middlesex and State of Massachusetts, have invented certain new and useful Improvements in Eyeletting-Machines, of which the following is a specification:

The nature of my invention consists, first, in an improved device for presenting the eyelets to the delivery device. The delivery-chamber of the machines can be supplied direct from the mercantile package of eyelets. Second, in an improved carrying or delivering device, by which each eyelet is taken on a stud and moved with precision to the piston-feeder. Third, in the piston-feeder, which is a vibrating sliding bifurcated lever, which seizes each individual eyelet (as it is presented from one of the studs of the delivery device) and passes it onto the piston-anvil. Fourth, in an improved device for holding the eyelet onto the piston-anvil while it is being placed in the eyelet-hole.

Figure 1 is a side elevation of my invention. Fig. 2 is a horizontal section of the same. Fig. 3 is also a side elevation, taken from a point of view opposite from that which Fig. 1 is taken. Fig. 4 is a horizontal section, taken from a lower plane than the section of Fig. 2, and is intended to show the operating-levers. Fig. 5 is an elevation showing the eyelet-piston and its adjuncts. Fig. 6 is a vertical section of the eyelet-piston and its adjuncts. Fig. 7 is a perspective view of a part of the eyelet-presenting ring. Fig. 8 is an elevation of a part of the eyelet-presenting ring. Fig. 9 is a horizontal section taken on line $x y$ of Fig. 8, showing also a part of the eyelet-delivering device.

Let A represent the base of the machine, to which the other parts are attached. H^3 , Figs. 1, 3, and 4, is a vertical plate of metal, surmounted by a fixed circular disk, H, Figs. 1, 2, and 3, and by a triangular plate, H^4 , Fig. 2, the edge of which is indicated by H^1 , Figs. 1 and 3. C, Fig. 2, represents a basin or chamber sunk in the disk H. The bottom of this basin or chamber C is convex—that is, highest in the center. $C' C' C' C'$, Fig. 2, are fixed elastic arms, curved as shown. E, Figs. 1, 2, 3, 7, and 8, is a ring of metal, placed in the

chamber C, as shown in Fig. 2. The outer circumference of this ring E has ratchet-teeth cut into it. M, Figs. 1 and 2, is a pawl, actuated by the lever N. By giving motion to the lever N, as will be hereafter explained, an intermittent motion is imparted to the ring E. F, Figs. 1 and 3, is a stationary cap, which fits over the basin C, and forms the eyelet-chamber. This eyelet-chamber has a tube, G, Figs. 1 and 3, which is to be connected by any suitable pipe with the mercantile package of eyelets, so that the supply to the eyelet-chamber may be constant.

The action of this part of the device may be explained as follows: The chamber C being filled with eyelets, and the machine being started, the ring E, Fig. 2, with its dentals $e^1 e^1 e^1 e^1$, Figs. 7, 8, and 9, moves in the direction of the arrow, Figs. 2 and 9. This action, in connection with the stationary arms $C' C' C' C'$, has a tendency to force the eyelets into the spaces $e^2 e^2 e^2 e^2$, &c., between the dentals $e^1 e^1 e^1 e^1$, &c.; and as the spaces are so shaped that the eyelet cannot enter them unless the eyelet stands flange down, it is evident that as the ring continues to revolve, each of the spaces $e^2 e^2 e^2 e^2$ will soon be filled with eyelets, and as the spaces $e^2 e^2 e^2 e^2$, &c., are inclined, as shown in Fig. 9, all of the eyelets have a tendency to work outward; but they are held in position by the ring H, Figs. 2 and 9, until they reach the point L, Figs. 2 and 9, where the ring H is cut, and where the carrier K, with its studs $k k^1 k^2$, &c., is located. The carrying device consists of a flat plate, K, Figs. 1 and 9, having studs $k k^1$, &c., projecting upward from it. The carrier K is located as shown in Figs. 1, 3, and 9. The plate K, Fig. 1, is connected to the sliding plate N^5 , Fig. 1, by means of links $K^1 K^2$. This sliding plate N^5 is operated by the lever N, which acts through the link N^6 and stud N^4 , Fig. 4, the stud N^4 being connected with the sliding plate N^5 . K^3 , Fig. 1, is a buttress, which prevents the link K^1 from swinging beyond the position shown in Fig. 1, so that when the plate N^5 is thrown in the direction of the arrow S, the carrier-plate K will have to move with it; but when the plate N^5 is moved backward, the friction-link K^3 , governed by the friction-screw K^4 , will resist the backward

motion of the carrier K. The resistance thus offered will cause the links K¹ K² to swing downward. This causes the carrier K to drop so as to withdraw the studs k k¹ k², &c., below the face of the plate H¹, Fig. 1—in other words, to draw them out of contact with the eyelets. The continued backward motion of the plate N⁵ will swing the links K¹ K² so as to bring the carrier-plate K to its lowest limits—that is, so it will come in contact with the top of the buttress K⁵. Then the carrier K will have to move backward with the sliding plate N⁵. (See Fig. 1.) The dropping and backward motion of the carrier-plate K is so limited that the first stud, k, will be immediately under the eyelet-delivery point L¹, Figs. 1, 2, and 9, of the ring E. Now, the next movement of the machine will cause the sliding plate N⁵ to move forward, the first action of which is to cause the links K¹ K² to swing toward a perpendicular line, since their upper ends are held by the friction-link K³. This throws the carrier-plate K directly upward, and causes the first stud, k, Fig. 9, to enter the eyelet T, which is at the delivery-point L¹ of the ring E. Now, the continued forward motion of the plate N⁵ will move the carrier K forward, because the link K¹ is stopped by the buttress K⁵ from swinging farther toward the perpendicular. Thus one eyelet will be carried forward on the plate H¹.

Let the above series of motions be repeated, and the eyelet on the first stud, k, will be left on the plate H¹ at a distance from the delivery-point L¹ equal to the forward motion of the carrier K. This distance is also equivalent to the space between the studs k k¹ k², &c., so that the next time the studs k k¹ k², &c., come up the stud k will take a new eyelet from the delivery-point L¹, and the stud k¹ will take the eyelet already passed out and forward it one space. A continued operation of the machine will take out a new eyelet at each motion, and forward the others already acted upon one space toward the end K⁸ of the piston-feeder K⁷ K⁸.

L, Figs. 1, 2, and 3, is a flat plate immediately over the studs k k¹ k². This plate L is provided with a number of light flat springs, m m m, &c. These springs rest upon the eyelets, and thus keep them in place while the studs k k¹ k², &c., are not in connection with them. K⁷ K⁸, Figs. 1, 2, and 3, is the piston feeding-lever, and is pivoted on a sliding pivot, K⁹, Figs. 1 and 3. This pivot slides in a housing, H². The end K⁷ of the lever is pivoted to a standard, K¹⁰, which is attached to the sliding plate K, so that, at each motion of the plate K, the levers K⁷ K⁸ will move back and forth, and also swing in a vertical plane—that is, as the plate K falls and retreats the end K⁸ of the lever will rise and retreat, and, upon the rising and forward motion of the plate K, the end K⁸ of the lever will fall and advance. These parts are so adjusted that, when the end K⁸ of the lever falls, it will grasp one of the eyelets that has been forwarded by the

studs k k¹ k², &c., and hold it in its fork-shaped mouth, as shown at K⁸, Fig. 2; then, its next motion being forward, the eyelet will be passed onto the piston or lower set P⁴, Figs. 1, 2, 3, 5, and 6. The piston or lower set P⁴, Figs. 5 and 6, slides in a stationary tube, P, Figs. 1, 3, 5, and 6. The top of this piston or set has a central opening, as shown at P⁴, Fig. 6, to receive the point of the upper set, and is concaved slightly, so as to offer a better seat for the eyelet. R and R, Figs. 1 and 5, are flat springs attached to a sleeve, P². This sleeve is held up by a spring, P³, and is limited in its motion on the piston P⁴ by the slot and pin P⁵, Figs. 5 and 6.

When the sleeve P² is thrown upward to its highest point, as shown in Fig. 5, then the upper ends of the springs R lie over the top of the piston P⁴, and grasp the eyelet T', as shown in Fig. 5. When the piston P⁴ is thrown up to its highest point—that is, so it shall be on a level with the table S², Figs. 1, 2, and 3—then the upper end of the sleeve P² will have come in contact with the stationary part H¹, as seen in Fig. 6, and will have been prevented from rising a distance equal to the distance P⁴ rises; and, as the springs R R are attached to the sleeve P², it is evident that the upper end of P⁴ will pass up beyond the top of the springs R R, these springs being so formed that the top of the piston P⁴ can pass between them, causing them to open and allow it (the top of the piston) to pass above the top of the springs R R. This action will release the eyelet and leave it in the eyelet-hole of the boot or shoe.

The motion of the piston or set P⁴ is regulated to correspond to the motion of the eyelet-feeding mechanism, so that an eyelet is taken onto the set at each motion. In case the eyelet is not left in the eyelet-hole of the article, and is carried down on the set, it will be pushed off at the next motion of the lever K⁸, and will be thus prevented from interfering with the action of the machine.

The vertical motion is given to the piston or lower set P⁴ by the lever N², Fig. 3, which, acting through the cam N⁷, gives motion to the lever O, the lever O being pivoted at O¹, and connected to the piston by the pin O², Figs. 3 and 5. While the eyelet is at the point of delivery, L¹, Fig. 2, awaiting the action of the carrier K, it is held steadily in its place by the spring L², Fig. 2.

The mouth K⁸ of the lever K⁷, Fig. 2, is provided with a small spring, K⁶, Figs. 1 and 2, which serves to steady the eyelet while being operated upon by the lever K⁸. S¹, Fig. 1, is a stud projecting downward from the table S², and serves as a guide for locating the eyelet-holes in the different halves of the work, so they may correspond with each other.

I claim as my invention—

1. In an eyeleting-machine, the combination of the basin C with the ratchet-toothed ring E, operating substantially as described, and for the purpose set forth.

2. In an eyeleting-machine, the combination of the basin C and elastic arm C' C' C' C' with the ring E, operating substantially as described, and for the purpose set forth.

3. The combination of the ring E with the spring L², operating substantially as described, and for the purpose set forth.

4. In an eyeleting-machine, the carrying device, consisting of the plate K, studs k k¹ k² k³, &c., plate L, and springs m m m, &c., operating substantially as described, and for the purpose set forth.

5. In an eyeleting-machine, the levers K⁷ K⁸,

made with the forked end at K⁸, and provided with a spring, K⁶, operating together substantially as described, and for the purpose set forth.

6. In an eyeleting-machine, the springs R R, in combination with the piston P⁴, operating substantially as described, and for the purpose set forth.

JOHN E. WIGGIN.
